UNITED STATES PATENT OFFICE.

EDWARD K. RABEY, OF DEANES, VIRGINIA.

SPRING-TIRE.

1,156,311.

Specification of Letters Patent. Patented Oct. 12, 1915.

Application filed December 16, 1914. Serial No. 877,558.

To all whom it may concern:

Be it known that I, EDWARD K. RABEY, a citizen of the United States, residing at Deanes, in the county of Nansemond and State of Virginia, have invented certain new and useful Improvements in Spring-Tires; and I do hereby declare the following to be a full, clear, and exact description of the invention, such as will enable others skilled in the art to which it appertains to make and use the same.

My invention relates to improvements in spring tires for vehicle wheels, and it is especially intended to provide a resilient construction which will give the desired cushioning effect as the vehicle travels over the road, and yet will be strong, durable and efficient, and not likely to get out of order.

My invention is also intended to provide an improved resilient construction of the character described which may be cheaply constructed without requiring expensive material, or difficult or expensive machine work.

My invention will be understood by reference to the accompanying drawings, in which the same parts are indicated by the same reference numerals throughout the several views.

Figure 1 is a side elevation of the complete wheel, parts being broken away; Fig. 2 shows a section on the line 2—2 of Fig. 1, and looking in the direction of the arrows; Figs. 3 and 4 are details of the intermediate springs used in the device shown in Figs. 1 and 2; and Fig. 5 is a modification showing the structure with these intermediate springs removed.

A represents the hub of the wheel provided with suitable spokes B and a felly C on which the felly band D is mounted in the usual way. The construction of wheel thus described differs only from the ordinary wheel in that the spokes are comparatively short and the felly is of comparatively small diameter relative to the complete diameter of the wheel.

Outside of the felly band D is secured the metal ring E, in the form of a channel, with side flanges e, and to the bottom of this channelled ring E the inner ends of the strips F are secured, which strips are made of resilient metal, such as spring steel, and are curved as shown in Figs. 1 and 2; the outer ends f of these springs F overlapping each other as shown in Fig. 1, and being se-

cured together by rivets f'. These overlapping ends form a tread for the wheel, which may be supplemented by an auxiliary tread secured thereto, as shown at G in Fig. 5.

In the structure shown in Fig. 1, between the spring strips F are preferably mounted intermediate or auxiliary springs H and I, which are normally metal strips bent when assembled into the shape shown in Figs. 1, 65 3 and 4; and when thus bent they tend to straighten out, thus forming a live spring. The springs when out of place tend to straighten out as shown in dotted lines in Figs. 3 and 4. Thus it will be seen that all 70 the springs used are live springs. One end h of the springs H is riveted to the overlapping ends of the contiguous springs F, and the other end h' projects between the two contiguous springs F and is riveted to the 75 outer one as shown in Fig. 1.

The other auxiliary spring I is U-shaped, and has one end i riveted to the back of the spring H, and the other end i' riveted to the inner end of the corresponding spring F 80 and secured with it to the channelled ring E. Thus, these several springs F, H and I are all connected together, and to the felly of the wheel, and the outer end of the springs F and both ends of the springs H form part 85 of the periphery of the wheel, and thus provide a very stiff and at the same time a resilient periphery which may be used without any additional reinforce if desired; but in certain cases it is desirable to provide an 90 additional tire arrangement such, for instance, as the strip of leather, or other suitable yielding material G, shown in Fig. 5, which is fastened to the circumference of the wheel in any convenient way. This 95 strip G will lessen the noise and will afford a better frictional engagement between the circumference of the wheel and the ground.

It will be seen that I provide a wheel composed of a series of springs bound together, and when inequalities of the road are encountered these springs will transmit the strains from one to the other throughout a large portion of the body of the wheel, and will thus distribute and ease same; thus lessening the wear on the individual springs, and also the strains thereon, and insuring the durability and efficiency of the device. I prefer to have these auxiliary springs H and I included in the structure shown in 110 Fig. 1, but where light vehicles are used, it may be feasible, under certain circum-

stances, to construct the device as shown in Fig. 5.

It will be obvious that the length of the spokes may be varied at will, thus reducing 5 the diameter of the felly, and rendering it possible to have the spring area of the wheel of greater or less radial diameter, as desired. Moreover, it will be seen that an ordinary 10 wheel may be cut down to fit a felly of small radial diameter, as shown, and the herein described spring attachment applied thereto.

It will also be obvious that the springs F, 15 H and I may be made heavier or lighter to meet the requirements of the vehicle body and of the load to be carried thereby.

It will be obvious that various modifications might be made in the herein described 20 device, and in the construction, combination and arrangement of parts without departing from the spirit of my invention.

Having thus described my invention, what I claim and desire to secure by Letters Patent of the United States is:—

25 1. A resilient tire arrangement for wheels, comprising a series of metal strips bent to

form substantially U-shaped springs having their outer ends overlapping and secured together, and their inner ends adapted to be fastened to the felly band of the wheel, with 30 a series of auxiliary springs interposed between said first-mentioned springs and connected to the same and to each other, substantially as and for the purpose described.

2. The combination with a wheel provided with a felly and felly band, of a series of resilient metal strips bent to form substantially U-shaped springs, having their inner ends secured to said felly band, and 35 their outer ends overlapping the adjacent 40 springs and secured thereto, with a series of intermediate resilient strips bent to form substantially U-shaped springs connected to the first-mentioned springs and to each 45 other, the whole forming a compound spring tire, substantially as described.

In testimony whereof, I affix my signature, in presence of two witnesses.

EDWARD K. RABEY.
